CLAIM

The ornamental design for a portable screw driving machine as shown and described.

DESCRIPTION

FIG. 1 is a perspective view of a portable screw driving machine showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings are for the purpose of illustrating portions of the portable screw driving machine that form no part of the claimed design.
